(57) CLAIM

The ornamental design for a tape dispenser, as shown and described.

DESCRIPTION

FIG. 1 is a top, front and side perspective view of a tape dispenser, showing my new design;

FIG. 2 is a top, rear and side perspective view thereof;

FIG. 3 is a front elevational view thereof;

FIG. 4 is a rear elevational view thereof;

FIG. 5 is a side elevational view thereof;

FIG. 6 is a side elevational view thereof, taken from the side opposite to that shown in FIG. 5;

FIG. 7 is a top elevational view thereof; and,

FIG. 8 is a bottom plan view.
